POURING SPOUT FOR CONTAINERS

Roscoe W. Shore, Jackson Heights, N. Y., assignor
to Alfred J. Chamberlain, Milwaukee, Wis.

Application November 3, 1932, Serial No. 641,024

3 Claims. (Cl. 221—11)

This invention relates to new and useful improvements in pouring spouts for containers.

The principal object of the invention is to provide a pouring spout which will pour and accurately control a stream of liquid from a container, without gurgling caused by the back flow of air from the orifice into the top of the container.

A further object of the invention is to provide a very simple self-contained unit which includes a protruding pouring spout which normally is contained within the can or drum itself.

It is further contemplated to provide the standard rolled edge beaded nozzle with a drawn plug closure equipped with a closing seal which makes the can non-refillable as a package until the original seals and sealing machine are available.

In detail the design has been so made as to prevent the trapping of air in the top of the can at any angular tilting position. If the can is full of liquid and the spout is pulled out to the pouring position, it is impossible to cause the liquid to trap air in the can as it flows out through the spout. This prevents the gurgling which is so troublesome in pouring liquids from ordinary containers with circular nozzles. This effect is obtained regardless of the viscosity of the liquid.

In the drawings:—

Fig. 1 is a perspective view of a container with the improved pouring nozzle projecting therefrom and in a pouring position, the plug and seal having been removed.

Fig. 2 is a sectional view showing the position of the pouring spout nozzle, plug and seal when the spout is sealed inside of the container.

Fig. 3 is a similar view to Fig. 2 but shows the pouring spout projecting through the nozzle, and in pouring position, the plug and the seal having been previously removed.

Fig. 4 is a diagrammatic view showing the relative position of the surface of the liquid as the container is tilted near the pouring point.

Fig. 5 is another diagrammatic view showing the level of the liquid and the air pocket condition in the top of the container as the liquid pours over the pouring spout.

Fig. 6 is a diagrammatic view showing the shape of the stream of liquid as it passes from the spout in pouring. This particular design of pouring spout produces a stream of relatively narrow cross-sectional dimension which is very valuable in pouring such materials as denatured alcohol into automobile radiators; or other examples where spilling of the fluid may cause injury.

The invention is particularly directed to a

pouring spout for a container having a projecting nozzle of standard design except that it is of a special elongated cross section which is fundamental with the results of perfect pouring.

The elongated nozzle is so mounted in the container as to provide a slot which if a vertical plane is passed through its long axis when the container is sitting level or upright as shown in Figs. 2 and 3, said plane will be at right angles to the level of the liquid in the container. Furthermore, it is contemplated to provide a pouring spout which can be pulled out through the slotted nozzle into a pouring position. This pouring spout is preferably of a purely channel type which provides side guiding flanges and a pouring edge through which the liquid flows smoothly and without top friction. There are two features which are essential in the perfect pouring of a liquid through an orifice, the one being that the liquid flows freely and without excessive friction through a weir type notch rather than through a completely closed opening such as a cylindrical pouring spout. It is a well known fact in hydraulics that a liquid flowing through an orifice with its top level free and exposed only to air rather than a restraining surface flows faster and more uniformly. Secondly, a liquid flowing from a container must be free of back pressure caused by the receding of the liquid in the can and atmospheric pressure on the outside of the can attempting to fill the space emptied of liquid. The slotted design of this invention provides a means for the liquid to be free at its surface level both as to the passage of the liquid and for the inflow of air over the surface of the liquid to fill the space emptied in the container.

In the drawings similar reference numerals refer to similar parts.

A container 1 having a head 2 is provided with a nozzle 3 upturned integrally therefrom and providing an orifice or passage through which the container may be discharged and vented when in a tilted pouring position as shown in Figs. 4 and 5. The nozzle 3 is preferably of elongated shape, thereby giving the discharge and venting means 45 referred to similar shape. This means is positioned so that a normal plane passing through its major axis when the container is in said tilted pouring position will be substantially at right angles to the pouring level of the liquid and also 50 intersect said level to locate the upper portion of the passage or orifice above the level for free venting of the container and to locate the remaining portion of the passage below the level for the discharge of the container. A beaded liner shell 4 55

with an outwardly turned flange 5 is securely pressed on to the nozzle 3 and the container head 2. Plug 6 is made to a flange fit in the top of the beaded portion of the liner shell 4. The plug 5 has a flange 7 which rests upon the bead of the liner 4. Between the flange 7 and the bead of the liner 4 is inserted a gasket 8 made of rubber or other suitable material for sealing in the contents of the can and a metallic seal 9 having downwardly turned edges 9a is pressed over the plug 6 and clinched in position with a mechanical sealing machine. The seal is made from thin metal and is provided with tongues 14 cut therefrom so as to act as tabs to be pulled off by hand when the can is opened. A pouring spout 10 of a channel design is hinged to the outwardly turned flange 5 of the liner shell 4. The pouring spout is made by forming a piece of sheet metal to conform in cross section closely to the shape of the elongated nozzle and comprises a pouring edge of cylindrical shape with two sides protruding upward therefrom to form side guides to restrain and guide the liquid to the pouring edge. These sides terminate in outwardly turned flanges 11 of the spout 10. To provide a tight fit between the pouring spout and the inner face of the container a U gasket 12 is fastened to the pouring spout flanges 11. In order to hold the pouring spout in position after it has been pulled through the nozzle two slight projections 13 are provided on the side walls of the pouring spout and at such a position as to engage the bead of the nozzle. The pouring spout 10 snaps into place whereupon these projections 13 lock it against return. When the container is packed, being filled with oil or other liquid, the pouring spout hangs downward within the nozzle of the container, the same usually being immersed in the liquid. This spout is entirely self draining with 40 in the container and is wiped clean on its sides when pulled out for use, making it very valuable for food products.

When the consumer receives the shipment the package is opened by stripping the metal seal 9 from the top of the nozzle 3 and tearing the tabs 14 away by hand. The plug is then removed breaking the gasket seal 8 of the plug flange against the nozzle bead. The pouring spout is then exposed to view and it is only necessary to 50 pull it upward through the nozzle into its locked protruding position. With the nozzle in this position the can is tilted so that the level of the liquid is substantially at right angles to a normal plane passing through the major axis of the 55 elongated nozzle.

It is obvious that many other designs involving different details of construction might be made with these principles but a preferred embodiment has been shown and these alterations would not

depart from the spirit of the invention as set forth in the appended claims.

Having fully described my invention what I claim as new and desire to secure by Letters Patent is;

1. A container of the character described, comprising a body having a top wall having an opening therein, a nozzle carried by the top wall about said opening and projecting outwardly therefrom, said nozzle having an outer member and an interfitting liner shell, said liner having its outer end fitting over the outer end of the outer member of the nozzle and having a flange at its inner end fitting in the container about the opening in the top wall, and a pouring spout hingedly connected to said flange, said spout being swingable from a position within the container to a position extending through the opening and the nozzle.

2. A container of the character described, comprising a body having a top wall having an opening therein, a nozzle carried by said top wall about said opening and projecting outwardly therefrom, said nozzle having an outer member and an interfitting liner shell, said liner having a bead at 25 its outer end fitting over the outer end of the outer member of the nozzle and having a flange at its inner end fitting in the container about the opening in the top wall, a pouring spout hingedly connected to said flange, said spout being swingable from a position within the container to a pouring position extending through the opening and the nozzle, and a closure for the opening, said closure having a member fittable over the outer end of the nozzle and interconnected with 35 the bead on the liner.

3. A container of the character described, comprising a body having a top wall having an opening therein, a nozzle carried by the top wall about said opening and projecting outwardly therefrom 40 to provide for the attachment of a closure for the opening, said nozzle having an outer member and an interfitting liner shell, the latter extending through the outer member of the nozzle, and a pouring spout hingedly connected to the liner at 45 the inner end thereof, said spout being swingable from a position within the container to a pouring position extending outwardly through the opening and the nozzle, said nozzle, opening, and spout being of complementary elongated form and 50 disposed with their major axes intersecting the level of the material passing through the spout from the container when the container is in a tilted pouring position with said axes extending upwardly to locate the vent provided by the upper 55 portions of the opening, nozzle, and spout above said level and the discharge provided by the lower portions of said opening below said level.
